UNITED STATES PATENT OFFICE.

REGINALD A. FESSENDEN, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

MEANS OF TRANSMITTING INTELLIGENCE.

1,170,969.

Specification of Letters Patent.

Patented Feb. 8, 1916.

Application filed December 23, 1907. Serial No. 407,750.

To all whom it may concern:

Be it known that I, REGINALD A. FESSENDEN, a citizen of the United States, residing at Brant Rock, in the county of Plymouth, 5 State of Massachusetts, have invented certain new and useful Improvements in Means of Transmitting Intelligence, of which improvements the following is a specification.

My invention relates to electric signaling 10 and more particularly to wireless signaling by electromagnetic waves.

In the accompanying drawings forming a part of this specification Figure 1 shows in diagram an arrangement for carrying out 15 the object of this invention. Fig. 2 shows an alternative arrangement.

The invention herein disclosed has for its object the securing of absolute secrecy in the transmission of wireless messages and transmission 20 without producing any disturbances on nearby stations, and the attainment of high speed, and the transmission and receipt of messages simultaneously.

In the practice of my invention, instead of 25 sending dots and dashes I send dots only, which are to be interpreted as dots and dashes according to the time of their receipt at the receiving station, the determination of whether a signal is a dot or dash being 30 thus impossible without a knowledge of the exact time interval employed. By this means in addition to absolute secrecy greater speed is obtained.

I also prefer to use my method of sending 35 by generating oscillations continuously and producing a signal by varying the frequency. I also prefer, at the receiving end to use my heterodyne method of receiving.

The method of operation can, however, obviously 40 be used with other well known methods of transmitting and receiving signals and I do not therefore limit myself to the particular arrangement herein described.

In Fig. 1, 11 is an antenna grounded, at 45 12; and 13, 14 are primaries of transformers connected to a source for continuously generating waves, for example the spark gap 15, a continuous current dynamo 16 and 50 variable resistance 17. 18 is a condenser and 19 an inductance used for tuning the high frequency oscillating circuit. 20 and

21 are metallic disks with insulating segments so arranged that one connects with its brush in advance of the other but the two 55 overlap in position, their shaft 20^a being driven by the electric motor 22, whose field current is regulated by the battery 23, and adjustable resistance 24. This motor is maintained at constant speed by any suitable means such as the tuning fork 25, by the method described in U. S. Patent 727,326. 26 and 27 are brushes mounted on the arm 28. This arm is attached to the gear disk 29, in such a way that on depressing the keys 30 and 31, and so closing the 60 circuits containing the local battery 33 and the clutch mechanism 34 the disk 29 will be revolved by the threaded shaft 34^a, to the left or right according to which of the 65 friction disks 34^b is in engagement with disk 34^c, and thus the position of the brushes is advanced or brought back. 35, 36, 37 are taps from the inductance 19. 38, 39, 43 are switches electrically actuated by the 70 keys 40 and 41 and the local battery 42. 44 is a coil attached to the diaphragm of the transmitter 45 and 46 is a fixed coil operated by the secondary coil 47' of the transformer whose primary is the coil 14. 48' is 75 the secondary coil of a transformer whose primary is 13. 47, 48, 49 are adjustable resistances. In operation the keys 40 and 41 being in the released position, the switch 50 being open and the circuit closer 43 being 80 pulled over to the left by the spring 51, and the switches 38, 39 closed the commutator disks 20 and 21, in revolving cause electromagnetic waves of three different frequencies to be radiated: 1: The normal frequency 85 which we will call 100,000. 2: A higher frequency when the brush 27 is on the metallic part of the disk 21, thereby short circuiting one portion of the inductance 19 by wire 49^a connected to the shaft 90 20^a of the disks, which frequency we will take as 100,100. 3: A still higher frequency when the brush 26 also comes on to the metallic portion of the disk 20, thereby short circuiting a still larger amount of the inductance 19. This we may take as 100,200. Three frequencies of 100,000, 100,100, and 95 100,200 are therefore radiated continuously in sequence with each other. On de-

- pressing the key 41 the switch 39 is opened and the sequence then becomes 100,000, 100,000, and 100,200. The depression of this key we may take as the sending of a dot.
- 5 On depressing the key 40 the switch 38 is opened and the sequence becomes 100,000, 100,100 and 100,000. The depression of this key we may take as the sending of a dash. In this way the signals are transmitted.
- 10 Assume now that messages are being transmitted by a station using this arrangement and being received at a station using a similar arrangement. At the receiving station the keys 40 and 41 are still in a released position but the switch 50 is closed and the circuit closer 43 is thrown over as shown to the right. Obviously oscillations will flow continuously through the coil 46, the oscillations being uninterrupted but the frequency varying in the sequence 100,000, 100,100, and 100,200. The received signals will flow from the antenna 11 through the coil 44 to ground, and no indication will be produced if the disks 20 and 21 rotate at the same frequency, and have the same angular position as the disks at the sending station. If, however, the disks are not in synchronism, musical chords will be produced and the operator at the receiving station depresses one of the keys 30 or 31 and so rotates the brushes 26, 27 until silence is obtained. If after a short period the chords begin to be heard again the operator moves the adjusting nut 52 on the tuning fork 25 in such a way to obtain synchronism. In actual operation it is found extremely difficult even by the use of compressed air condensers, constant temperature boxes, etc., to maintain the high frequency circuits at the sending and receiving stations absolutely constant, but this is not necessary, as the operator, instead of adjusting the brushes to zero sound, adjusts them until a single note is heard instead of a chord, since when this is the case the disks are in synchronism and phase. Also it is impossible to maintain this synchronism absolutely, and after a longer or shorter period of time the chords begin to be audible again, and gradually swell in intensity, but the operator controls this by depressing the keys 30 and 31, so that the chords never rise above a barely audible intensity and so maintains synchronism. Assume now that the operator at the sending station depresses the key corresponding to the key 41. The oscillations transmitted by the sending station will then have the sequence 100,000, 100,000, and 100,200, and this will be the sequence received by the coil 44. As the sequence in the fixed coil 46 is 100,000, 100,100, and 100,200 beats of 100 per second will be formed between the second members of the two series, *i. e.* a musical note having that frequency will be heard by the ear of the operator, the receiver 45

being attached to the operator's head. A note of this frequency is recognized by the operator as representing a dot. On the key corresponding to 40 being depressed at the sending station, the sequence sent out will be 100,000, 100,100, and 100,000 and beats will now be produced between the three members of the series having a frequency of 200 per second, and the musical note of this frequency will be understood by the operator to represent a dash. In operation therefore, when the high frequency circuits are identical in frequency spaces will be represented by silence, dots by a musical note of 100 per second and dashes by a musical note of 200 per second. Should the frequencies differ by say 150 per second, spaces will be represented by a musical note of 150 per second, dots by a musical note of 250 per second and dashes by a musical note of 350 per second.

The following points are obvious: 1: That no other station can interpret the message transmitted without knowing the number of commutator segments and their exact speed of revolution, and as there is no means whereby an outside station can determine this, absolute secrecy is obtained. 2: Also that since the oscillations are generated continuously and of constant strength, (the resistances 47, 48, 49 being used to regulate this where necessary) and merely the tune is slightly changed therefore no disturbance will be produced on other stations unless they are using exactly the same range of tune. This is for the reason that even if the electrical oscillations are received by the other station, no sound will be produced on account of the oscillations being continuous and uninterrupted. 3: Also that greater speed can be obtained, since there is no space necessary between the dot and dash elements in sending a letter. For instance the Morse letter D sent the present way occupies a time equal to 9 dots whereas by the method herein described it occupies the time of three dots.

Fig. 2 shows the apparatus adapted to sending and receiving simultaneously. Elements identical with Fig. 1 are numbered identically. Instead of the oscillatory circuit containing the discharge gap 15, condenser 18, and inductance 19, acting directly on the secondary 48', it acts through the primaries 53, 54, 55, 56 on the circuit containing the secondaries 57, 58, 59, 60, the variable capacity 61, the resistances 62, 63, the fixed coil 64 and the primary 65. The coil 44 instead of being attached to the antenna is connected as shown to the middle point of the above mentioned circuit through the inductance 66 and variable capacity 67. With this arrangement it is possible for the operator to listen in at the same time that he is sending, since the coil 44 being in a

neutral position is unaffected to any extent by the currents induced by the high frequency source.

Having thus described my invention and illustrated its use, what I claim as new and desire to secure by Letters Patent is the following:

1. In electric signaling apparatus, the combination of a current controlling device in uniform motion at the sending station and a current controlling device in uniform motion at the receiving station, means to adjust the motion of the latter device independently of the former, but synchronously therewith, and means to cause impulses emitted from the sending station by means of the said controlling device to produce different effects at the receiving station according to the relative positions of the said two synchronous current controlling devices at the time of sending.

2. Electric signaling apparatus comprising a generator and a receiver, two synchronous frequency controlling devices respectively at the sending and receiving stations, means causing impulses due to said frequency controlling devices to normally annul each other's effects, and means to produce an indication by altering the relative phases of the synchronous devices, the indication depending upon the relation of phases, substantially as described.

3. Electric signaling apparatus comprising means for continuously sending a series of cycles of impulses, means to maintain independently at other stations a series of similar cycles, and means to produce a signal by altering the character of the individual impulses in the transmitted cycle.

4. Electrical signaling apparatus comprising means to locally maintain a stream of cycles of impulses, means to annul their effects by independent but synchronous cycles of impulses sent from another station, and means to sensibly indicate changes in the character of the individual impulses in the cycles sent.

5. Electrical signaling apparatus comprising sending and receiving circuits having independent means to maintain synchronous streams of orderly cycles of impulses in each circuit, means to normally annul their effects on each other, means to variously alter the character of the impulses in a cycle in one circuit, and means in the other by which said alterations produce sounds of predetermined character, for signaling.

6. Electric signaling apparatus comprising means to automatically send separate cycles of impulses divided into groups of predetermined character, a receiving indicator and means at the receiving station to normally suppress the effects of said cycles of impulses sent, means to vary the character of several of the groups in the cycles sent,

and means to produce at the receiving station different indications according to the group in the cycle which is changed.

7. Electric signaling apparatus comprising means to send a continuous series of groups of impulses of predetermined character, devices to alter the frequency of one of said groups to represent a dot, and another of said groups to represent a dash, receiving mechanism adapted to respond in a different way for the dot groups and the dash groups, substantially as described.

8. Electric signaling apparatus comprising means to send a continuous stream of electric impulses, means to separate said stream into predetermined cycles of wave trains of different character, and means to alter said character, and receiving mechanism adapted to respond with different indications according to the one of the trains in the cycle which is altered in character.

9. Electric signaling apparatus comprising devices sending a continuous series of recurring regular cycles of wave trains, means to alter the frequency of particular cycles, a receiver, controlling devices at the receiving station adapted to cause the receiver to respond to said waves sent, with a different indication for each cycle frequency.

10. Electric signaling apparatus comprising means to continuously send a stream of electromagnetic waves, devices to separate said stream of waves into cycles of groups of varying frequency, means to vary the frequency in any one of the groups, and a receiving apparatus adapted to respond with different kinds of indications dependent upon the order of succession of the frequencies sent.

11. Electric signaling apparatus comprising devices for sending a continuous series of impulses in predetermined cycles of different frequencies, devices for altering the frequency of any group in the cycle, and a receiving mechanism adapted to produce an indication varying in character according to the particular group of waves whose frequency is altered for signaling.

12. In wireless telegraphy, the method which comprises sending continuously orderly cycles of groups of impulses, varying the frequency of particular groups in the cycle, and at the receiver producing a different kind of indication thereby, according to the group of impulses in the cycle which is altered in character.

13. In wireless telegraphy, the method which comprises sending continuous series of cycles of impulses respectively differing in characteristics, varying groups in the cycles and at the receiving station actuating an indicator by selecting the particular group in a cycle whose frequency is varied.

14. In wireless telegraphy, the method of signaling by changing the frequency of par-

ticular groups in a cycle of varying groups of the impulses without interrupting the continuity, and producing an indication dependent for its character upon the change 5 in frequency.

15. The method of wireless signaling which comprises sending and receiving a continuous stream of impulses, periodically altering the characteristics of such impulses 10 in orderly groups of waves at the sending station, and at the receiving station actuating an indicator with different characters according to the order of succession of the groups whose characteristics change.

15 16. The method of electric signaling which consists in sending and receiving a continuous stream of impulses in series having normally uniform intensity and signaling by changing the frequency of impulses periodically 20 with a varying order of succession of periods, substantially as described.

17. The method of electric signaling which consists in sending and receiving a continu-

ous train of impulses divided into distinct cycles and varying the cycle so that it has 25 one character to represent a dot and a different character to represent a dash, in a signaling code.

18. The method of electric signaling which comprises maintaining two independent current controlling devices in synchronism respectively at the sending and receiving stations, and effecting a signal by their joint action, sending and receiving separate elements of a signal at different phases of the 30 movement of the current controlling devices and thereby differentiating the elements of the signal.

In testimony whereof I have hereunder signed my name in the presence of the sub- 40 scribed witnesses.
